UNITED STATES PATENT OFFICE

EDWARD B. ROBY, OF TROY, NEW YORK, ASSIGNOR TO S. AND R. FOLDING MACHINE COMPANY, INC., OF GREEN ISLAND, NEW YORK, A CORPORATION OF NEW YORK

FOLDING MACHINE

Application filed July 14, 1926. Serial No. 122,307.

The invention broadly relates to improvements in folding machines and more specifically to improvements in folding machines of the type wherein a heated bed-plate, infolders and a head carrying a die operate in synchronism to fold a blank.

In machines of this general character, the die is of a collapsible nature, and the infolders are in the form of reciprocating slides. 10 The blank is initially pressed between the bed-plate and the die carried by the head and the infolders then move in to fold the blank over the die. The die is next collapsed and withdrawn from engagement with the blank, 15 and, finally, the table is raised slightly to press the blank against the infolders and to complete the folding operation.

Among the principal objects which the present invention has in view, are:—To provide improved means for operating the various elements of the folding machine in synchronism; to provide a folding machine wherein synchronous motion is imparted to the folding elements from a single shaft, hereinafter termed the main shaft, through cams and other machine elements carried by said shaft; to provide a folding machine wherein the die is automatically caused to collapse and expand; to generally improve the 20 construction of the collapsible die; to provide novel means for synchronously actuating the infolders; to provide a resilient shock-absorbing connection between the bed-plate and its actuating means; to provide means for automatically withdrawing the folded blank from the machine after the folding operation has been completed; to provide a friction brake for controlling the movements of the various 25 folding elements; to provide a safety mechanism for preventing injury to the operator of the machine; and generally to provide improvements in folding machines with a view to simplifying and cheapening the construction and of rendering the same more efficient 30 in operation.

With the above and other objects in view, the invention further consists in the arrangements of parts and details of construction more specifically pointed out in the following description of the accompanying drawing.

ings forming a part of this specification and wherein like reference characters refer to the same elements throughout the various figures.

In the drawings:

55

Figure 1 is a side elevation of the machine with part of the frame broken away to show details of the automatic means for withdrawing the folded blank from the machine.

60

Figure 2 is a front elevation of the machine.

65

Figure 3 is a plan view of the machine.

Figure 4 is a plan view but with the head removed and the top plate partly broken away to show details of the infolder construction.

65

Figure 5 is a side elevation looking from the right of Fig. 2 with parts broken away to show further details of the infolder construction.

Figure 6 is a vertical section of the machine 70 on the line 6—6 of Figure 1 but with the head, bed plate and top plate in elevation.

Figure 7 is a vertical section of the machine 75 on the line 7—7 of Figure 2 but with the head, top plate and friction brake in elevation.

Figures 8 to 12, inclusive, illustrate the position of the folding elements at various stages in the folding operation.

Figures 13 to 17, inclusive, show the positions of the actuating means for the folding elements at the stages of the folding operation illustrated in Figures 8 to 12.

Figure 18 is a sectional view of the head cam showing the safety device in elevation 85 and with the main shaft partially broken away.

Figure 19 is an elevation of the same cam with the safety device out of operation.

90

Figure 20 is a view similar to Figure 19, but showing the safety device in operation.

Figure 21 is a bottom view of the head showing the character of the collapsible die.

Figure 22 is a horizontal section through 95 the head on the line 22—22 of Figure 8.

Figure 23 is a detail view partially in section of the automatic means for withdrawing the folded blank.

Figure 24 shows the shape of the blank 100

prior to its being subjected to the folding operation.

Figure 25 shows the blank after the first folding, and

5 Figure 26 shows the blank after the second and final folding.

The machine of the present invention is particularly adapted to be motor driven, although other types of drive may, if desired, 10 be employed. As shown in the drawings, a horizontal platform is bolted or otherwise secured to the frame, 10, of the machine near its foot. This platform preferably comprises two parallel beams, 11, and 12, of circular 15 cross-section and a staging, 13, carried by the beams to which a motor, 14, is attached. The motor drives a pulley, 15, on shaft, 16, by means of a belt, 17, which belt is guided by loosely rotating idle pulleys, 18, and 19. 20 A member, 20, carries the idle pulleys and is pivotally supported on shaft, 21, of the idle pulley, 19. This shaft is non-rotatably held in position by arms, 22 and 23, carried by beams, 11, and 12.

25 In order to prevent the machine from racing, a foot operated friction brake of the character shown more particularly in Figures 2 and 7 is employed. The member 20, is provided with a projecting arm, 24, to which a link, 25, and a rod, 26, are pivotally secured in any suitable manner. This rod, 26, extends through a small opening in the staging supporting the motor and through a hole in a lever, 27, which is pivoted on the beam, 12. 30 A nut, 28, is threaded on the end of the rod, 26, thus providing an abutment for the lever. The free end of the lever has bolted thereto a foot-piece, 29, for the operator of the machine. The upper end of the link, 25, is 35 fastened to one end of a link, 30, the other end of which is pivotally attached to the frame of the machine. The pivoted link, 30, is partially curved to embrace the pulley, 15, and the exterior of the belt driving the same.

40 When the foot-piece is depressed by the operator the pivoted link is also depressed and acts as a brake against the pulley, 15, and also prevents the belt from coming off. By means of this friction brake the operator 45 is enabled to retain complete control of the action of the machine at all times.

On the shaft, 16, there is a worm, 31, which meshes with the worm gear, 32, keyed to the main shaft, 33, of the machine and driving 50 the same. As indicated in Figure 6, the main shaft is supported in bearings 34, and 35, carried by the frame of the machine. The cams and other elements for imparting the requisite motions to the various operating parts of 55 the machine are keyed to this shaft.

As shown in Figures 6 and 7, a wiper cam, 36 is fastened to the end of the main shaft, 33. The wiper acts upon a roller, 37, carried by plunger, 38, which works within a sliding 60 rod, 39. The bed-plate, 40, of the machine

is threaded on the top of the sliding rod, 39, which rod is mounted for reciprocating movement in bearings, 41, and 42, provided in the frame of the machine. The bed-plate is sunk in a wall formed in the center of the machine. It is adapted to be heated when the machine is operating. For this purpose, an electrical heating coil may, if desired, be embedded in it. The plunger acts upon the sliding rod through a spring, 43, or other yielding and resilient means and causes intermittent reciprocating movement of the rod and bed-plate as the wiper rotates. The spring acts as a cushion for the bed-plate and absorbs any shocks to which it may be subjected.

70 The head of the machine indicated generally by the numeral, 44, is adapted to move in synchronism with the movements of the bed-plate. The head is carried by a bracket, 45, which is equipped with two arm portions, 46, and 47. The arm portions are provided with bearings, 48, and 49, adapting them for sliding movement on the reciprocating rod, 39, and on rod, 50. The upper end of the rod, 50, 75 fits in a bearing, 51, and the lower end carries a flange, 52, which is bolted to the staging, 13, and maintains the rod, 50, fixedly in position. The bracket carrying the head is guided in its movements by an element, 53, which is 80 attached to the upper part of the frame of the machine.

85 Bolted to the arm, 46, of the bracket, 45, is a member, 54, which serves as a carriage for the roller, 55. Another roller, 56, projects from an offset portion, 57, of the arm, 47, and is carried by a transverse horizontal shaft, 58, which shaft extends through a slot, 59, in the offset portion, 57, and is fixedly secured to lever, 60. The latter is pivoted to the arm, 47, by a bolt, 61. The roller, 56, can thus be 90 adjusted by loosening the bolt and changing the angular position of the lever after which the bolt is tightened, it being understood that the shaft, 58, slides in the slot provided therefor to permit this adjustment.

95 Vertical motion is communicated to the head through the bracket, 45, from the main shaft by a cam, 62, which acts upon the rollers, 55, and 56. The head is positively actuated in both directions and is caused to descend by the cam acting upon the roller, 56 and to ascend by the cam acting upon the roller, 55. The cam is provided with a safety mechanism to prevent injury to the hand of the operator should he be guilty of carelessness or inadvertence in the discharge of his duties. This safety mechanism will be more particularly described hereinafter.

100 The head of the machine carries a die which 105 is automatically caused to collapse at the correct stage of the folding operation and to be withdrawn from engagement with the article being folded.

110 To a central shank, 63, is clamped, as by a 115

130

bolt, 64, a flat flange member, 65, which is one of the die plates. As shown in Figure 8, the shank is made hollow throughout a portion of its length and fits over a male element, 66, which is driven through a hole in plate 67, and wedged therein. A transverse pin, 68, retains the shank and its associated flange in place, and the plate is fastened to the head by means of bolts, 69.

10 The plate has cut in its surface a plurality of T-shaped or dove-tailed grooves which receive slides, 70. An L-shaped angle iron, 71, is rigidly bolted to each slide. These angle irons carry flat flanges, 72, which form the collapsible plates of the die. Each slide is provided with a pin, 73, which extends through slots, 74, in the plate, 67, and into a helical groove, 75, cut in the bottom of disk, 76, within in the head. A shaft, 77, is integrally formed 15 with the disk and extends through a journal box, 78. A small gear, 79, is fixedly bolted on the top of the shaft, which gear meshes with a rack, 80. A guide, 81, which is fastened to the head, bears against the back of the rack and holds it in mesh with the gear.

20 When the rack is reciprocated, the gear and the disk are oscillated thereby, and, due to the helical groove in the disk, the pins carried by, and operating, the slides, are moved back and forth in the slots in the plate, and the slides and their associated angle irons and flanges are moved with them. The die is thus caused to collapse and expand by movement 25 of the rack.

30 Reciprocating motion is imparted to the rack by a bar, 82, which is pivotally attached by a bolt, 83, to a link, 84, and operated thereby. A link, 85, is rigid with the link, 84, and the two links are pivotally mounted by a bolt, 40 86, on the bracket, 45, and form a bell-crank lever. The free end of the link, 85, is provided with a roller, 87, which bears against the surface of a cam, 88, on the main shaft of the machine and is yieldingly maintained in 45 engagement therewith by a coiled spring, 89, one end of which is secured to the bar 82 and the other end to the bracket carrying the head (as shown in Figure 3 by means of eyelets or equivalent devices.

50 As the main shaft rotates, the cam, 88, actuates the roller, 87, and imparts reciprocating motion to the rack through the links and the bar, which motion of the rack causes the die carried by the head to collapse and expand in the manner heretofore described.

55 The infolders of the machine are operated from the main shaft by a cam, 90, thru rocking levers, 91, which are all pivotally mounted on a shaft, 92, supported in the frame of the machine. Each lever is provided with two arms, 93, and 94, which carry rollers, 95 and 96. The levers are positively moved in both directions by the cam, 90, acting on the rollers. As shown in dotted lines in Figure 65 5, the cam is stepped so as to provide a time

lag between the movements of the levers. The outer lever is first moved by the cam and after a short period of time the middle lever is moved and finally after another short period of time the inner lever is moved. The 70 reason for the above construction will become apparent as the description proceeds.

The levers are guided in their movements by flat bars, 97, which are clamped together in spaced relation by bolts, 98. The bars are rigidly secured to the frame of the machine near its top.

The tops of the levers are rounded off to form knobs, 99, which fit in mortises in the blocks, 100, which blocks are fastened to the circular concentric rings, 101. When the levers oscillate they cause a certain amount of rotation of the rings which slide on ball bearings 102.

For the purpose of illustration, I have 85 shown the machine as adapted to fold a pad for men's garters. The shape of the blank is shown in Figure 24. The edges 103, are first folded then the edges, 104, are folded. In order to produce these folds, it is only necessary that two of the rings be employed and therefore the outer ring does not operate any infolders but runs idle. Of course, it will be understood that with blanks requiring three stages of folding, the outer ring will be employed, and, in fact, the machine may be equipped with any number of levers and rings to perform folding operations of any number of stages.

Three infolders, 105, are used to produce 100 the folded edges, 103, and slide in guideways provided therefor in the plate, 106, which is attached to the top of the frame over a plate, 107, which covers the rings. Each infolder, 105, is provided with an oblique slot, 108, into which fit pins, 109, which are carried by the middle ring. The plate, 106, has circular slots, 110, through which the pins extend. As the ring rotates counter-clockwise, as seen 105 in Figure 4, due to the action of the rocking lever, the infolders, 105, are caused to move inward by the action of the pins in the oblique slots, and subsequent clockwise rotation of the ring will cause the infolders to move 110 backward out of engagement with the blank that is being folded.

Similarly three infolders, 111, are employed 120 to produce the folded edges 104, which infolders also slide in guideways provided in the plate, 106. These infolders are operated in a manner similar to the infolders, 105, by the action of pins carried by the inner ring and extending through oblique slots in the infolders. A top plate, 112, is attached to the top 125 surface of the frame of the machine and covers the mechanisms just described. The top plate is cut away sufficiently at its center to allow the blank being folded to be forced by the die carried by the head of the machine 130

against the bed plate and between the infolders.

When the blank has been folded, it is withdrawn from the machine by a picker operating automatically and in synchronism with the movements of the other elements and is conveyed to a chute, 113, which is attached to the front of the machine and wherein the folded blanks are collected.

10 The picker comprises a rigid bar, 114, curved near its lower end and pivoted by a bolt, 115, to a portion of the frame of the machine. A thin curved arm, 116, extends through a hole in the upper end of the bar 15 and has a right angular bend, as shown in Figure 2, so that its free end extends in the direction of the center of the machine. The free end terminates in a downwardly directed point and there is a small leaf spring, 117, 20 which is attached to the arm in proximity to the end. A small link, 118, is secured to that end of the arm that projects through the bar so that the arm and the link rotate as a unit. A spring, 119, is coiled 25 around the arm. One end of this is attached to the arm and the other end to the bar in such a way as to urge the pointed end of the arm in a downward direction. The link, 118, forms one of the links of a four-bar linkage, 30 the other three links being the bar, 114, a rod, 120, one end of which is connected to the link, 118, and a trigger, 121, which is pivoted on the bar, 114, by a pin, 122. To one 35 end of the trigger the other end of the rod is connected. The other end of the trigger projects in the path of a stud, 123, which is carried by the wiper, 36. The arm, 116, is only capable of moving through a small angle. The extent of its upward movement is 40 determined by a stop, 124, which is attached to the bar, 114, and coacts with the trigger, 121, and the extent of its downward movement is determined by the stop, 125, which is also attached to the bar, 114, and coacts with 45 the link, 118.

The picker is provided with a dash-pot (Figure 23) which is of conventional structure and comprises a cylinder, 126, within which slides a perforated piston 127. The 50 piston rod, 128, is attached to the bar, 114, by means of a bolt, 129, and the dash-pot is pivotally secured to the support, 130, by a bolt, 131. The dash-pot is allowed to swing around the bolt, 131, as the picker operates. 55 The support, 130, has projecting therefrom a limb, 132, which serves as a back rest for the picker.

The retracted position of the picker is shown in Figures 1 and 14, to which position it is biased by gravity and rests against the limb, 132, of the support, 130. As the wiper rotates, it carries the stud, 123, with it. When the stud strikes the end of the trigger its first result is to lift the arm, 116, 60 to its elevated position. Further rotation of

the stud causes the parts of the picker to swing around the bolt, 115, as a unit to the position shown in Figure 13, in which position the front end of the arm, 116, is above the folded blank. When the stud is carried past the end of the trigger, the arm, 116, falls under the action of gravity and of the spring, 119, and the pointed end together with the leaf spring, 117, engages the blank. The leaf spring retards the downward movement of the end of the arm and prevents the same from striking the blank with such force as to punch a hole in or otherwise spoil the blank. The picker then falls back to its retracted position and the blank is swept into the chute thereby. The dash-pot insures that a certain time interval shall elapse between the time that the stud passes the end of the trigger and the time that the picker falls back into its retracted position so that during the interval the arm shall have dropped onto the blank. The coil spring, 119, is employed to accelerate the speed with which the arm falls when released.

90 The sequence of steps in the folding operation is disclosed in Figures 8 to 12 inclusive and the various positions of the cams and levers corresponding to these steps are shown in Figures 13 to 17 inclusive.

95 Figures 8 and 13 show the position of the parts at the completion of the folding operation. The head has been lifted to its uppermost position by the cam, 62, and the wiper, 36, is so positioned that the bed-plate is in its lowest position. The bar, 114, operated by the trigger, 121, and stud, 123, had moved the picker arm, 116, in over the piece. The expansion of the die carried by the head has been brought about due to the lowering of the roller, 87, and link, 85, by the cam, 88. 100 The infolders are in their withdrawn position. The picker arm is ready to drop down and remove a folded blank and a fresh blank is shown resting on the infolders where it has been placed by the operator of the machine.

105 The stud now passes the end of the trigger and the picker is swung to its retracted position and carries the folded blank with it. The bed-plate moves up and the head descends under the action of their respective cams, and the die presses the blank against the bed so that the edges of the blank are bent at right angles, as shown in Figure 9. The infolders are then moved in by the rocking levers acted upon by the cam, 90, the infolders, 105, first moving to fold the edges, 110 103, over the die and immediately afterwards the infolders, 111, moving to produce the folded edges, 104. The cam, 88, then raises the roller, 87, as shown in Figure 16, 115 and the die is caused to collapse and to withdraw from between the folds, as indicated in Figure 11. Simultaneously, the bed-plate is lifted up slightly higher by the wiper, 36, 120 125 130 135

and presses the folded edges of the blank against the infolders. Finally the head is raised, the infolders are withdrawn, the bed-plate is lowered, and the above described 5 operation is ready to be repeated.

During the folding operation heat is continuously supplied to the bed-plate so that bed-plate, die and infolders serve to iron the folded blank and it is ready for the sewing 10 machines as soon as it is withdrawn.

The cam, 62, which operates the head, is provided with a safety device which functions to prevent it from lowering the head should the hand of the operator be beneath 15 it. The upper roller, 55, bears directly on the cam surface but the lower roller bears on a flange, 133, fastened to the side of the cam. This flange extends partially around the cam and its outer edge conforms substantially to 20 the contour of the cam. A tapering dog, 134, which is pivoted to the cam by a bolt, 135, in one position (Figure 19) forms a continuation of the flange. A lever, 136, is pivotally secured to the cam as by a pin or other 25 equivalent means. One end of this lever is bent and extends through a slot, 137, in the side of the cam and is fastened to the rear of the dog. The other end of the lever is bent at an oblique angle and extends through 30 a hole in the rim of the cam in the path of the descending upper roller, 55.

As the cam rotates, the dog under the action of gravity tends to assume the position shown in Figure 20. When the head descends the roller, 55, strikes the oblique end 35 of the lever, the dog is moved to the position shown in Figure 19, and the roller, 56 is caused to bear against the outer surface of the dog and flange, and the head is positively 40 moved downward thereby. If, however, the hand of the operator, or other obstacle, should be in the path of the descending head, the head would be arrested in its descent, the roller, 55, would not strike the oblique end 45 of the lever, and the roller, 56, would ride on the inner surface of the dog and flange. The head, therefore, would not be positively caused to descend, but would, on the contrary, be maintained at an elevated position 50 so that the operator of the machine could easily disengage his hand without serious injury to same.

Alterations and variations may be made in the above described machine without departing from the spirit of the invention and I desire that it be construed as limited only by the state of the prior art and the scope of the appended claims.

I claim:—

1. In a machine of the class described, a frame, means carried thereby operating in synchronism to fold a blank, a rigid bar pivoted to a part of the frame and biased to its retracted position, a single arm pivotally attached to the free end of the bar and adapted

to assume a raised and lowered position, the free end of said arm being extended downwardly for engagement with the blank, and means for positively moving said bar to its advanced position while maintaining the arm in its raised position and for releasing said arm when the bar is advanced to allow the free end of the arm to engage the folded blank, and for withdrawing said bar to cause the arm to sweep the blank from the machine. 70

2. In a machine according to claim 1, a spring for biasing the arm to its lowered position. 75

3. In a machine of the class described, a frame, means carried thereby operating in synchronism to fold a blank; a rigid bar pivoted to a part of the frame and biased to its retracted position, an arm pivotally attached to the free end of the bar, a trigger pivotally secured to the bar near its pivoted end, 80 a rod operatively connecting the trigger and the arm, and forming with the trigger, the arm, and the bar a four bar linkage, means for limiting the movement of said four bar linkage, a shaft mounted in the frame of the machine, means for rotating said shaft, and a stud rotating with the shaft and adapted to engage the trigger to move the bar to its advanced position. 90

4. In a machine of the class described, a movable head, a bracket for the support of the head, a projecting member associated with the bracket and adapted when operated to cause operation of the bracket and head, a rotary member including a flange, said flange having an outer side and an inner side, and means for causing the projecting member to ride on either of said sides, said means being operative in accordance with whether or not an obstacle is in the path of the head. 95

5. In a machine of the class described, a movable head, a bracket for the support of the head, two arms carried by the bracket, a cam disposed between the two arms, means for rotating said cam, a dog pivotally attached to the cam, and a lever also pivotally attached to the cam, one end of said lever being secured to the dog and the other end projecting in the path of one of the arms as the head is lowered. 105

6. In a machine of the class described, a movable head, a bracket for the support of the head, a projecting member associated with the bracket and adapted when operated to cause operation of the bracket and head, a rotary member including a flange, said flange having an outer side and an inner side, and means for causing the projecting member to ride on either of said sides, said means including a pivotally-mounted dog, 110 and means operated in accordance with whether or not an obstacle is in the path of the head for controlling the dog. 120

7. In a means for folding the edges of a blank over a die, a plurality of slides, a plu- 125

rality of concentric rings, operative connections between the slides and rings, and means for rotating the rings successively in predetermined synchronism to move the slides successively.

5. 8. In a means for folding the edges of a blank over a die, a plurality of slides, a plurality of concentric rings, operative connections between the slides and rings, pivoted levers for rotating the rings, and means for rocking the levers successively in predetermined synchronism to move the slides successively.

15. 9. In a means for folding the edges of a blank over a die, a plurality of slides, a plurality of concentric rings, operative connections between the slides and rings, pivoted levers for rotating the rings, a single shaft for mounting the levers, and means for rocking the levers successively.

20. 10. In a machine for folding a blank, a disk having a single spiral slot extending spirally from the center of the disk, a plurality of slides radiating and extending radially from the center of the disk, said slides being adapted to perform a folding operation upon said blank, pins associated with the slides and extending into said slot, and means for rotating said disk around its center as an axis.

25. 11. In a machine of the class described, a frame, means carried thereby operating in synchronism to fold a blank, and automatic means for removing the folded blank from the machine, comprising a single arm having a downwardly extending free end, means for moving the arm in over the blank, allowing it to fall on the blank, and retracting it to sweep the blank from the machine, and means 30 comprising a leaf spring mounted adjacent the end of the arm to cushion the contact of the arm with the blank.

40. In testimony whereof, I have signed my name to this specification this 30th day of June, 1926.

EDWARD B. ROBY.
